Primary Examiner — Darcey E Gottschalk(74) *Attorney, Agent, or Firm* — LADAS & PARRY LLP(57) **CLAIM**

The ornamental design for a pre-form with handle, as shown and described.

DESCRIPTION

FIG. 1 is a perspective view a pre-form with handle showing my new design;

FIG. 2 is a right-side elevational view thereof;

FIG. 3 is a left-side elevational view thereof;

FIG. 4 is a rear elevational view thereof;

FIG. 5 is a bottom plan view thereof; and,

FIG. 6 is a top plan view thereof.

The broken lines in the figures illustrate portions of the pre-form with handle that form no part of the claimed design.

1 Claim, 5 Drawing Sheets(56)
